UNITED STATES PATENT OFFICE

IVAN P. DE MAY, OF NEWARK, NEW YORK

FOLDABLE GUARD FOR JOINTER MACHINES

Application filed April 5, 1930. Serial No. 441,932.

This invention relates to a guard for use in conjunction with planing mills, and the primary object of this invention is to provide a foldable guard for covering the knives of a jointer machine to protect the fingers of the operator from the knives.

A further object of the invention is to provide a foldable guard of the character above mentioned adapted to be contacted by the work whereby the guard may be sufficiently folded as to allow the work to pass, and which when the work has passed will spring back into position over the knives.

As comprehended by the present invention, the guard as before intimated will not require any manual operation, the guard being operated through the medium of suitable spring means whereby the guard will be moved into an effective position over the knives after the work or board to be jointed has passed.

Other objects and advantages of the invention will become apparent during a study of the following description, taken in connection with the accompanying drawings, wherein:

Figure 1 is a top plan view of my improved guard, the same being illustrated as used on a conventional type of jointer machine,

Figure 2 is a side elevational view of the guard showing the same in collapsed position.

Figure 3 is a side elevational view of the guard, the guard being shown in spread position.

Figure 4 is a fragmentary detail sectional view taken through the guard for more clearly illustrating the hub mechanism of the guard,

Figure 5 is a horizontal transverse sectional view taken substantially on line 5—5 of Figure 4,

Figure 6 is a detail view taken substantially on the line 6—6 of Figure 1.

With reference more in detail to the draw-

ings, it will be seen that I have shown in plan view a conventional type of jointer machine designated generally by the reference character M, which machine among other parts comprises the usual work table 50, the work treating knives, and the work guide 6.

The guard comprehended by the present invention comprises a vertically disposed shaft 7, the lower end of which is suitably mounted in a bracket 8 on one side of the table 5 as clearly suggested in Figure 1. The shaft is held within the bracket 8 through the medium of a set screw 9.

The guard proper includes a plurality of 60 blades, preferably three, the blades being designated by the reference characters 10, 11 and 12 respectively. Each of the blades is substantially identical in formation, being preferably made of metal and of elongated 65 triangular configuration.

The blades are disposed one upon the other, the blade 12 being lowermost blade, the blade 10, the uppermost blade and the blade 11 the intermediate blade. The blades 70 are of the configuration shown to advantage in Figure 1 and at its innermost arcuate edge, the lowermost blade 12 is provided with an arcuate flange 13 corresponding in contour to the edge contour of said blade 12.

The hub for the guard is designated generally by the reference character H. This hub H comprises a plurality of sections one for each of the blades, the lowermost blade 12 at its apex or smallest end being formed integrally with the relatively large hub section 14.

The intermediate blade 11 at its smallest end formed integral with the intermediate hub section 15, and the uppermost blade 10 85 at its smallest end formed integral with the upper end of section 16. Each of the hub sections is provided with a central opening for receiving the upper end of the shaft 7, and arranged within the opening of the re- 90

spective hubs is a suitable annual bearing 17 as shown to advantage in Figure 4.

For retaining the hub of the guard on the upper end of the shaft 7 there is threaded on the uppermost end of the shaft a pair of lock nuts 18 and 19 respectively, while the lower end of the hub section 14 rests on a suitable disk 20 keyed to the shaft 7 through the medium of a suitable set screw 21, the disk 20 forming a closure cap for the lower end of said hub section 14.

Arranged within the hub section 14 and convoluted about the shaft 7 is a coil spring 22, one end of which is anchored in the disk 20 as at 23, and the other end of which is anchored in the wall of the hub section 14 as at 24.

It will be noted that the guard blades 10 and 11 respectively are formed on the upper end of their respective hub sections, the hubs therefor suitably spacing the blades with respect to one another to permit freedom of movement of the blades.

Integral with and extending diagonally across the blade 12 at the free end thereof is an inverted U-shaped member 25, the leg of the member 25 at the corner of the blade 12 engageable in a notch 26 formed in the upper corner of the intermediate blade 11 30 at the free end of said blade.

A similar member 27 is likewise formed integral with and extends diagonally across the blade 11 adjacent the free end thereof, and has one leg thereof receivable in a notch 35 28 in the upper corner of the blade 10 at the free end of said blade.

Thus it will be seen that the members 25 and 27 respectively act as an interlocking connection between the blades.

Under action of the spring 22, the lowermost blade 12 is normally swung in a direction to the right in Figure 1, so that as is obvious through the medium of the connector members 25 and 27 the blades are disposed in that position suggested in Figure 1, so that the guard is in an open or extended position for covering the knives of the jointer.

Obviously, as the work designated generally by the reference character W passes into contact with the knives, the work will be disposed between the guide 6 and the flange of the lowermost blade 12, thus striking the flange 13 of said blade and moving the blade inwardly or to the left in Figure 1, thus 55 slightly contracting the guard against the action of the spring 22 whereby the work is free to continue its direction of movement.

When the work moves out of contact with the flange 13 under action of the spring 22 the blade 12 will be again swung outwardly thus spreading the blades of the guard whereupon the guard will be suitably extended for again covering the knives of the jointer thus protecting the fingers of the operator from the knives and at the same time requiring

no effort on the part of the operator for swinging the guard to a suitable position so as to not interfere with the work W.

It will be further noted that the top nut or cap 19 is provided with a laterally extending stop S, while the hub 16 of the guard blade 10 is provided with a vertically disposed stop S' for abutting engagement with the stop S. Thus it will be seen that the stops S and S' cooperate to prevent the guard from folding in the wrong direction, this being apparent when it is considered that the blade will swing over toward the right of Figure 1 when the guard is in an unfolded position, with the result that the outer end of the 80 jointer knives would be left uncovered, however the blade 10 is prevented from so swinging toward the right through the medium of its stop S' contacting with the stop S as is apparent from a study of Figures 1 and 2. 85

It is thought that from the foregoing description, taken in connection with the accompanying drawings a clear understanding of the operation, utility and advantages of this invention will be had by those skilled in the art without a more detailed description. 90

Even though I have herein shown and described the preferred embodiment of my invention, it is to be understood that the same is susceptible to changes fully comprehended by the spirit of the invention as herein described, and the scope of the appended claims. 95

Having thus described my invention, what I claim as new is:

1. A guard for jointer machines comprising in combination a shaft, means for vertically adjusting the shaft on the machine, a hub rotatably mounted on said shaft and including a plurality of independent sections, a disc keyed to the shaft for supporting said hub on the shaft, a spring convoluted about said shaft internally of one of said hub sections and having one end thereof engaging said one hub section and the other end thereof engaging said disc, a blade carried by each of said hub sections, one of said blades provided with a flange adapted to contact the other of said blades for rotating the blades opposite to the action of said spring, a stop supported on said shaft, a stop on a second of said hub sections co-acting with the first mentioned stop to limit swinging movement of said second hub section under action of said spring. 105

2. A guard for the cutter members of a jointer machine, said guard comprising a rotatably mounted hub, said hub including a plurality of independent sections, means normally rotating one of said sections in one direction, a blade carried by each of said sections, said blades being arranged relative to one another and adapted to be opened and closed fanwise above said cutter, said blades provided with cooperating means whereby 110

upon movement of the first mentioned hub section, said blades will transmit movement from one blade to the other for swinging said blades in one direction, a flange on one of said blades adapted to contact with the remaining blades upon swinging movement of said one blade in an opposite direction for simultaneously swinging all of said blades in a corresponding direction.

10 In testimony whereof I affix my signature.
IVAN P. DE MAY.
